United States Patent Office

Des. 230,823
Patented Mar. 19, 1974

230,823

RETRACTABLE KNIFE

Daniel Gluck, Woodmere, N.Y., assignor to Columbia Broadcasting System, Inc.

Filed Oct. 10, 1972, Ser. No. 296,427

Term of patent 14 years

Int. Cl. D8—03

U.S. Cl. D8—99

FIG. 2

FIG. 1

FIG. 3

FIG. 4

FIG. 5

FIG. 6

FIG. 1 is a perspective view of a retractable knife showing my new design;

FIG. 2 is a top plan view thereof;

FIG. 3 is a bottom plan view thereof;

FIG. 4 is a side elevation view of the side thereof opposite to the side shown in FIG. 1;

FIG. 5 is an end view thereof, as viewed from the left in FIG. 4; and

FIG. 6 is an end view thereof, as viewed from the right in FIG. 4.

I claim:

The ornamental design for a retractable knife, substantially as shown and described.
